IGNAZ SCHÜBEL, OF BERLIN, GERMANY.

GAITER.

1,199,436.

Specification of Letters Patent. Patented Sept. 26, 1916.

Application filed July 2, 1912. Serial No. 707,232.

To all whom it may concern:

Be it known that I, IGNATZ SCHÜBEL, subject of the King of Prussia, residing at No. 3 Kochstrasse, Berlin, Prussia, German Empire, have invented new and useful Improvements in Gaiters, of which the following is a specification.

My invention has special reference to a new and useful improvement in or relating to 10 a fastener for gaiters or leggings, shoes, corsets or like wearing apparel, and particularly to that type of fastener, in which a rack member fixed to one part of the gaiter, legging, shoes or like wearing apparel is intended to be passed into a guide-way and 15 engaged by a spring catch secured to the other part of the gaiter, legging, shoe or like wearing apparel.

It has been already proposed to apply 20 a fastener to gaiters, leggings, shoes, corsets or other wearing apparel the fastener having a curved toothed metal strap secured at the one edge of the wearing apparel, which metal strap is locked and held in the 25 locked position by a spring pressed ratchet. The hitherto known constructions of this class have the disadvantage that in undoing the wearing apparel or in adjusting the locking position the fastener must always be 30 held fast by hand in the unlocked position; therefore the undoing of the wearing apparel or the adjusting of the locking position can be effected only by both hands; for by one hand the locking member must be held 35 out of engagement with the curved toothed metal strap and by the other hand the desired adjusting of the locking members can be operated. It is obvious that the undoing of a wearing apparel provided with 40 such a fastener is very wasteful of time.

The object of my invention is to provide a fastener which can more readily be unlocked with only one hand and held automatically in the unlocked position.

45 A further object of my invention is to provide a very effective fastener which is very cheaply manufactured, durable and not affecting the fashionable aspect of the gaiter or legging.

50 In compliance with my invention I provide at or near the longitudinal edge of one side of the gaiter a short metal strap slightly curved to adapt itself to the round outside to the leg and I provide also at or near the longitudinal edge of the opposite side of the gaiter or legging a suitable guide-way

to receive said metal strap, said guide-way being provided with suitable locking means for engaging said metal strap and retaining the same in the locked position. Said locking means are adapted to be automatically engaged by the metal strap when pushed into said guide-way, for closing or locking the gaiter, and also to be readily released from engagement with the said metal strap, 60 when the gaiter is desired to be opened or put off. In providing the said guide-way or guide-ways at or near one of the longitudinal edges of the gaiter, I prefer to form the metal-blade generally employed for 65 stiffening the leather of the gaiter along said longitudinal edge, with a cranked portion or recess opposite the metal strap secured at or near the longitudinal edge of the opposite side of the gaiter. Thus, in applying the 70 gaiter, the said curved metal strap requires only to be pushed into the said guide-way at the opposite side, and when the said strap has been sufficiently pushed through the said guide-way to make the gaiter fit 75 well, the locking-device will automatically engage the said metal strap and lock the same in the desired position.

In order that my invention can be clearly understood and carried into effect, an embodiment of my invention is illustrated by 85 way of an example by the accompanying drawings in which—

Figure 1 shows the improved fastening means applied to the lower end of a gaiter; 90 the upper leather of the gaiter is partly shown broken away to better disclose the fastening means below. Fig. 2 is a cross-section drawn on line A—B of Fig. 1; the locking means are shown in the locked position. 95 Fig. 3 is a longitudinal section drawn to line C—D of Fig. 1; the locking means are shown out of engagement. Fig. 4 is a similar section to Fig. 3, the locking means being shown in the locked position. 100

Referring to Figs. 1—4 *a* is the upper side of a gaiter and *b* the lower side of the same. Along the longitudinal edge of the said upper side *a*, a metal blade 1 is secured between the leather and its lining for stiffening and strengthening the leather in the well known manner. 2 indicates a cranked portion integral with the metal blade 1, hereinafter called the "stiffening blade," and forming a guide-way. To the lower end *b* of the gaiter or legging a curved toothed metal strap 6 is secured by its rear 105

end, as shown in Fig. 1, the free forward end of the strap being adapted to be inserted in the guide-way 2 in its normal or locked position. The teeth 8 formed in the metal strap are preferably integral with the metal strap and have their inclined back directed to the front (Fig. 2). The curved metal strap or rack member 6 has a central longitudinal slot 13 cut in it. The curved metal strap 6 is held normally in its locked position by means of a spring plate 3 extending across the cranked portion 2. The one or lower end of the spring is riveted or otherwise secured to the stiffening blade 1, the free end 4 passes through a hole or slot 5 provided in the stiffening blade 1 and underlying the same in a proper distance. The said spring 3 normally bears flatly against the metal strap in the space between two teeth 8 of the metal strap 6 and holds the latter in its locked position as clearly shown from Figs. 1 and 2. It is obvious from the foregoing that when the curved metal strap 6 is being shifted into the guide-way, below the said spring 3 crossing the cranked portion 2 the spring 3 will slide over the back of said teeth 8 and automatically catch behind the steep side of one of the teeth 8 as soon as the metal strap 6 is no farther pushed on. Said metal strap 6 thus will be locked against being withdrawn from the guide-way 2 and underneath the spring 3 and the two sides of the gaiter or legging are fastened to each other in such position as has been selected by more or less shifting the strap 6 into the guide-way 2 of the stiffening blade 1. The tightness of such fastening position may be adjusted by pushing the strap 6 farther on or by withdrawing it for the length of a tooth 8 or more by only one hand.

In order to release the spring catch 3 from engagement with the rack member 6 I provide according to my invention a key 9 having a flat stem and a handle or finger piece 10 projecting outside the legging or gaiter. The flat stem has a contracted or cylindrical portion by which it is enabled to turn within a bearing 12 provided on the lower surface of the spring 3. Normally, the stem of said key takes a position parallel to the flat spring 3, but on giving said key 9 a quarter of a turn by the side of said handle 10, the edge of the flat key will strike the bottom of the cranked portion 2, as shown in Fig. 3, and the spring 3, thereby, will be raised and lifted out of engagement with the teeth 8 of the strap 6; the said strap 6, then, may be withdrawn. On turning the said key 9, its flat portion turns within the longitudinal slot 13 of the metal-strap 6.

It is obvious that the spring 3 will be held automatically out of engagement with the rack member and the key 9 will be prevent-

ed from accidentally turning by friction of the spring occurring upon the key in whatever position the key is brought.

In the illustration the fastener is shown applied to gaiters or leggings, however it can be applied to garments, shoes, corsets, or other wearing apparel without departing from the idea of my invention.

Having now fully described and ascertained the nature of my invention and the manner by which it may be performed, what I claim as my invention is;

1. In a fastener for gaiters or leggings the combination of a guide-way with locking means comprising a rack member secured to the lower side of the gaiters or leggings at one end, the free end being adapted to engage the said guide-way and a spring catch and with a key adapted to release the spring catch out of engagement with the rack member and hold automatically the same in the unlocked position.

2. In a fastener for gaiters or leggings the combination of a guide-way integral with the stiffening blade of the gaiters or leggings with locking means comprising a rack member secured to the lower side of the gaiters or leggings at one end, the free end being adapted to engage the said guide-way, and a spring catch, and with a key adapted to release the said spring catch out of engagement with the rack member and automatically hold the same in the unlocked position.

3. In a fastener for gaiters or leggings the combination of a guide-way forming a part of the stiffening blade, with locking means comprising a rack member fixed at one end to the lower side of gaiters or leggings, the free end being adapted to engage the said guide-way, and a spring catch consisting of a spring plate extending across the guide-way normally bearing against the said rack member, fixed at the one end to the said stiffening blade, the free end passing through a slot or hole provided in the stiffening blade and underlying the same in a proper distance, and with a key adapted to release the said spring catch out of engagement with the said rack member and automatically holding the same in the unlocked position.

4. In a fastener for gaiters or leggings the combination of a guide-way forming a part of the stiffening blade, with locking means comprising a rack member fixed at the one end to the lower side of gaiters or leggings, the free end being adapted to engage the said guide-way and a spring catch consisting of a spring blade extending across the guide-way normally bearing against the said rack member, fixed at one end to the stiffening blade, the free end passing through a hole or slot formed in the said stiffening blade and underlying

the same in a proper distance, and with a key adapted to release the spring catch out of engagement with the said rack member and to automatically hold the same in this position, the key having a flat stem and a handle or finger-piece, projecting outside the gaiter or legging, the stem being provided with a contracted or cylindrical portion journaled in a recess of the said spring

catch and adapted to raise the spring catch 10 out of engagement.

In testimony whereof I have signed my name to this specification in the presence of two subscribing witnesses.

IGNAZ SCHÜBEL.
